APPARATUS FOR ISOLATING ZONES IN WELLS
Nolan J. Rogers, Houma, La., assignor of forty-nine percent to Charles D. Golson, Houma, La.
Filed June 26, 1962, Ser. No. 205,261
14 Claims. (Cl. 166—57)

This invention comprises a novel and useful apparatus for isolating zones in wells and more particularly pertains to an apparatus by which selected portions of a well bore and the formation contiguous thereto may be effectively isolated from the remainder of the well bore and formation by freezing the liquid in the well bore at these locations and in the adjacent formations to thereby provide a barrier preventing communication and flow into or out of said selected portions of the well bore and formations.

It is frequently desirable to isolate selected regions in a well bore and the formation zones contiguous thereto for various purposes. The present prevailing practice of inserting a mechanical plug in the well bore such as a seal or packer to effect a fluid tight seal with the wall of the well bore is accompanied by many disadvantages and difficulties attending the installation of the packer or seal, interruption to flow of fluid in the well during the installation of the packer or seal, and the subsequent removal of the packer or seal when its services are no longer required. Since these difficulties are well known to those familiar with oil well and other deep well operations, a further and more specific discussion of them is deemed to be unnecessary for the purpose of this invention. It may be noted however, that these undesirable conditions are even more prevalent when it is desired to conduct a series of tests in a well bore for selectively isolating different zones thereof to determine the flow characteristics or the production from individual zones, since this necessitates a repeated establishing of a series of seals to isolate selected zones in order to test the production or flow of the latter, and then remove the seals to repeat the operation at other zones.

It is therefore the primary purpose of this invention to provide an apparatus which will greatly facilitate the isolation of selected zones in a well bore and in the contiguous formation penetrated by the well bore.

A further object of the invention is to provide an apparatus which will enable the establishment of a seal and the removal of the latter when its use is no longer required, to be effected with ease and certainty regardless of the shape or configuration of the well bore at the site which is to be sealed.

A further object of the invention is to provide an apparatus which will enable seals to be readily applied to selected regions of a well bore without necessitating the use of heavy, cumbersome, and time requiring equipment and techniques of installation and removal of the seals.

Yet another object of the invention is to provide an apparatus whereby a self-contained seal establishing unit or units may be mounted in tubing or pipe strings and which will not interfere with the flow through the string until such time as it is desired to effect the establishment of or the release of a seal at a selected site.

A still further object of the invention is to provide an apparatus which will enable a seal to be quickly established or released from a selected site in a well bore for isolating a selected zone or region and wherein the operation of establishing or releasing the seal may be entirely effected and controlled from the surface.

A still further object of the invention is to provide an apparatus which will enable the use of drilling fluid to initiate the sealing action and to effect a release of the seal when desired.

More specifically, it is a further object of the invention to provide an apparatus whereby a refrigerating effect

may be applied at a selected region in a well bore to effect freezing of the drilling fluid therein and in the contiguous formation in order to establish a seal and thus isolate a selected zone.

5 And a final important object of the invention to be specifically enumerated herein resides in the provision of an apparatus which will enable the freezing of the drilling fluid to effect the establishment of a seal and the thawing of the frozen drilling fluid when it is desired to release the seal and which will in no way interfere with the use of other types of seals where desired.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

10 FIGURE 1 is a fragmentary view in vertical section through a well bore in a formation and indicating the manner in which the principles of this invention are to be applied thereto;

15 FIGURES 2—5 are successive views taken upon an enlarged scale and in vertical central section through the apparatus of this invention respectively upon the planes indicated by the section lines 2—2, 3—3, 4—4 and 5—5 of FIGURE 1 and showing the position of the parts of the apparatus in their inoperative or non-sealing positions;

20 FIGURE 6 is a detail view in horizontal section taken substantially upon a plane indicated by the section line 6—6 of FIGURE 3;

25 FIGURE 7 is a detail view in horizontal section taken substantially upon the plane indicated by the section line 7—7 of FIGURE 5;

30 FIGURE 8 is a further horizontal section taken substantially upon the plane indicated by the section line 8—8 of FIGURE 5;

35 FIGURES 9 and 10 are detail views illustrating the operation of the device; and

40 FIGURE 11 is a group perspective view of the actuating means for initiating operation of the seal forming portion of the apparatus.

Referring first to FIGURE 1 it will be observed that the numeral 10 designates a well bore extending through a subterranean formation to a strata 12 which it is desired for any of various reasons to isolate from the well bore and the rest of the formation. In accordance with this invention a refrigerating device indicated generally by the numeral 14 is attached to the lower end section 16 of a drilling string, a tubing string or a pipe string of any desired character whereby the refrigerating device can be positioned and moved in the well bore to the desired location therein. When so placed, the refrigerating device heretofore kept inactive is rendered active in a manner to be subsequently set forth whereby

45 it will produce a refrigerating action which will freeze the liquid in the well bore on opposite sides of the selected zone in the well bore and the contiguous region or strata 12 which is to be isolated. This refrigerating action will freeze the liquid between the refrigerating device and the wall of the well bore so as to produce plugs of frozen liquid in the well bore and in the contiguous portions of the region adjacent thereto and thus effectively seal and prevent any flow through the well bore from or into the selected region or strata. By

50 the provision of suitable conduits extending through the refrigerating device and opening into the selected strata or region of the well bore, various operations such as testing, acidizing or the like can be employed while the frozen seals are maintained in place. Thereafter,

change relation therewith thus completely removing the closure seals and permitting the resumption of flow through the well bore.

Reference is now made specifically to FIGURES 2-5 for a description of a preferred and suitable form of refrigerating apparatus in accordance with this invention.

The refrigerating device 14 consists of an elongated body of a sufficient diameter to be readily inserted into or removed from a well bore and moved along the well bore to and from a selected region or location. Although it may be of a one-piece or unitary construction, it is preferably formed of a plurality of sections detachably secured together and which preferably have a smooth cylindrical continuous exterior surface of uniform diameter throughout. The body of the refrigerating device consists of a lower section 20, see FIGURE 5, having a refrigerant storage chamber 22 therein and having a screw threadedly engaged plug or closure bottom wall 24 therefor. Adjacent but spaced from the top of the lower section of the storage chamber section the latter is provided with a partition 26 thereacross which separates the storage chamber 22 from a refrigerant delivery chamber 28, with the partition 26 having passage means establishing communication between the chambers 22 and 28 as set forth hereinafter.

A discharge piston 30 has a fluid tight sliding seal and engagement with the wall of the refrigerant storage chamber 22 and is moved upwardly under the influence of the pressure in the liquid within the well bore and which communicates with the bottom side of the piston 30 by means of the inlet passage 32. Consequently, as liquid refrigerant is delivered from the chamber 22 the pressure of the liquid in the well bore entering the passage means 32 will force the piston 30 upwardly and assist in expelling refrigerant liquid from the chamber 22.

At its upper end, the lower section 20 is internally threaded at 34 to receive therein a pair of spaced externally threaded plates 36 and 38. Above the plate 36, by means of tapering internal threads 40, the lower section 20 is secured to the externally threaded portion of a section 42 which comprises a lower expansion chamber of the refrigerating device.

At its upper end, the lower expansion chamber section 42 is internally threaded and thus is secured to the lower end of a spacer section 44 of any desired length. This spacer section may consist of a single pipe section or a plurality of such sections joined together in order to provide the requisite length as will be apparent hereinafter.

As shown in FIGURE 3, the uppermost portion of the spacer section or sections 44 is internally threaded and engages the lower end of an upper expansion chamber section 46. At its upper end, the latter is internally threaded to engage the connector or coupling member 48 threadedly secured to the lower end of a further section 50. The latter in turn is internally threaded to engage an adapter section 52 whose upper end is internally threaded and receives therein the diametrically enlarged flanged extremity 54 of a section or member 56. The latter is slidably received in the axial bore of a sleeve or coupling member 58 whose upper end is threadedly engaged upon the lower extremity of the string 16.

When the sections are assembled in this manner, as shown in FIGURE 1, the entire refrigerating device can be handled as a unit. It will be understood that appropriate lengths of spacer sections 44 be interposed between the lower expansion chamber section 42 and the upper expansion chamber section 46 in order to obtain any desired spacing between these two expansion sections and thus enable them, as shown in FIGURE 1, to extend through the zone of the well bore and the contiguous region of the strata 12 to enable refrigerat-

ing action as set forth hereinafter to be positioned on opposite sides of this zone and region.

Referring now to FIGURE 2 it will be observed that the adapter section 52 and the member 56 are slidably supported by the connector section 58. For this purpose, the section 56 has a diametrically extending axially elongated bore 60 therethrough and a pair of retaining pins 62 each threadedly engaged in the sleeve 58 are slidable in the diametrical bores or slots 60. These pins engage the stem of a collar 64 below the laterally enlarged upper portion 66 thereof to support this collar. The member 56 has an axial bore therethrough in the upper portion of which is provided a cylindrical groove 68 having a shear pin or locking ring 70 therein against which the upper surface of the member 64 abuts.

Secured to and supported by the member 64 as by means of a screw threaded engagement as shown in FIGURE 2 is the upper end of a tube 72. The latter may consist of a single member or a plurality of sections secured together. This tube has a sliding engagement in the bore 74 of the bottom wall 76 of the adapter section 52, and an O-ring or other sealing means as at 78 may be provided to insure a fluid tight sealed engagement where the tube passes through the bore 74.

At its lower end, the tubular tubing 72 is connected as by a coupling member 80 to a further tube 82 which likewise has a sliding engagement in the bore 84 of the transverse partition 36 at the lower end of the upper expansion chamber 46. Continuing downward from the upper expansion chamber section 46, the tube member 82 extends through the spacer section or sections 44, having a sliding engagement in a bore 88 in each of the transverse walls 90 of these sections. From thence the tube section 82 extends downwardly through the bore 92 in an intermediate partition 94 secured in the upper portion of the lower expansion chamber section 42 as by means of a pair of split rings each indicated at 96. Continuing downwardly through the lower expansion chamber section 42, the tube is slidably received in the bore 98 of the bottom wall 100 of the lower expansion chamber section. The tube at its lower end extends through aligned bores in the two plates 36 and 38 and is provided with a closure plug or cap 102 at its lower end which lies in the refrigerant delivery chamber 28 previously mentioned.

This tube serves a number of important functions in the operation of this device. Its upper end is open and by means of the axial bores through the associated members, it communicates directly with the interior of the string 16 by means of which various liquids or fluids may be passed downwardly through the tube to effect various functions of operation some of which are set forth hereinafter. In addition, in one or more of the spacer sections 44 which lie between the upper and lower expansion chamber sections 46 and 42, the tube is provided with a port 110 which is adapted to register with a passage 112 formed in the wall or partition 90 of the spacer section 44. Thus, when the tube is appropriately positioned vertically in the device, so that the port 110 will register with the passage 112, communication is established between the interior of the tube, and the interior of the string 16 and the well bore between the upper and lower expansion chamber sections of the device. In this manner, fluid can be withdrawn from a selected region of the bore with which the passage 112 registers for testing or other purposes or liquids can be applied to the well bore at the selected zone by being forced downwardly through the tube.

In addition to its functions of serving as a flow tube to receive fluid from a selected portion of the well bore, and as a means for supplying various agents to the formation from the surface, the tube also serves as a means to control the refrigerating action of the device.

In each of the expansion chambers there is provided an expansion coil. Thus, the lower expansion casing 42 has a lower expansion chamber 114 therein and the walls of this chamber are lined with an expansion coil 116. In a

similar manner, the upper expansion chamber section 46 has an upper expansion chamber 118 therein and an upper expansion coil 120 is disposed in this chamber. A refrigerant delivery tube 122 has its lower end threadedly engaged in the bottom wall 100 of the lower expansion chamber section 42 where it communicates with a refrigerant passage 124. This passage in turn communicates with a valved outlet passage 126 extending through the upper plate 36 and which thus communicates with the valving chamber 128 disposed between the two plates 36 and 38. A further passage 130 extends through the lower plate 38 and has continuous communication with a valving chamber 128. Aligned with the passage 126 in the lower plate 38 is a valve bore 132 in which is slidably received the lower end of the refrigerant control valve 134. As shown in FIGURE 11, this valve is a cylindrical body having a diametrical slot 136 therethrough in which is slidably received an actuating member in the form of a cam finger 138 carried by an actuating piston 140. The latter slides in the valve actuating chamber formed between the plates 36 and 38 so that, as shown particularly in FIGURES 5 and 10, fluid pressure to the right of the piston 140 will drive the latter towards the left. Owing to the engagement of the cam finger 138 in the slot 136 of the control piston 134, the latter will be reciprocated in its piston bore 132. As the piston 140 moves towards the left, the valve is shifted downwardly so that its upper end will uncover the seat at the lower end of the passage 126 thus establishing free communication between the delivery chamber 128 by way of the passage 130, the valve chamber 128 and the passage 126 to the passage 124 and thus to the interior of the refrigerant delivery conduit 122. Pressure fluid is supplied to the right side of the piston through the previously mentioned tubes 72, 82 and a port 142 in the lower end of the tube section 82 which registers with the actuator chamber in which the piston 140 is transversely slidable through an aperture partition 141 comprising an end wall for the actuator chamber. Any suitable means may be provided for effecting the return of the piston to the right end of this chamber and thus effect the lifting of the control valve to its seated or closed position cutting off communication between the valve chamber 128 and the passage 126.

It will thus be apparent that by applying a predetermined pressure to the interior of the tubes 72 and 82, the control valve may be opened to permit the discharge of refrigerant from the delivery chamber 28 into the delivery conduit 122.

From the delivery conduit, at the lower end of the tube 122, the lower expansion coil 116 is connected as by means of a coupling 144. At its upper end, the expansion coil 116 as shown in FIGURE 4 is connected at its extremity 148 to a discharge conduit 150 which latter is secured in the partition member 94 and extends therethrough, through the partition 90 of the spacer unit or units 44, and finally as shown in FIGURE 3 through the upper expansion chamber where it terminates and opens into the upper end of the latter.

It will be further apparent from FIGURE 3 that the refrigerant delivery conduit 122 at its upper end terminates in a bore in the partition 86 of the upper expansion chamber section 46 and the lower end of the upper expansion coil 120 is connected as by a fitting 152 and passage 154 with the bore 156 into which the upper end of the delivery conduit 122 extends. The upper end of the upper expansion coil 120, terminates as shown at 158 in the upper end of the upper expansion chamber 118. Thus the two refrigerant expansion coils discharge at the upper end of the upper expansion chamber and into the auxiliary expansion space 160 of the section 50.

As will be appreciated, during this expansion of the compressed refrigerant, the latter will absorb heat and thus effect a chilling or refrigerating action thus causing the liquid in the well bore adjacent the upper and lower expansion chamber sections to be frozen solid and form a plug or seal in the well bore at these locations. It will

be appreciated that this seal is formed independently of the nature of the well bore itself, that is, it is not dependent upon the bore being of uniform size, shape or physical characteristics.

5 Referring now to FIGURES 5 and 8, it will be observed that the partition 26 of the refrigerant storage section 20 has a passage system of any convenient character such as that indicated generally by the numeral 161 therethrough by means of which refrigerant from the storage chamber 10 22 may pass through the partition 26 and enter the delivery chamber 28 to be discharged therefrom under the control of the control valve as set forth hereinbefore.

It is believed from the foregoing that the operation of the apparatus will now be readily apparent. With the 15 storage chamber charged with a liquid refrigerant under pressure such as liquid oxygen or the like, and with the parts in position shown in FIGURES 2-8, the refrigerating device, connected to the string 16 is introduced into and lowered in a well bore until the device reaches the 20 desired location therein. For this purpose, the spacer section 44 of the device is of appropriate length to extend entirely across the zone in the bore and the region in the contiguous formation which is to be isolated. It will be observed that this operation can be effected while drilling mud or other fluid is being discharged by means of the 25 tube 72, 82 and the open port and passage 110, 112 in the manner shown in FIGURE 9. Thus, the device can be installed during a drilling operation if the string 16 is a drilling string. With the device installed, that is, properly located with respect to the zone in the bore to be isolated, it is merely necessary to increase the pressure within the tubes 72, 82 to the desired extent. This will cause the piston 140 to be moved towards the left as viewed in FIGURE 5, until the piston assumes the position shown in FIGURE 10, at which time the same actuating finger 138 will open the control valve 134 to the position shown in FIGURE 10, at which time the cam actuating finger 30 erant from the storage chamber upwardly through the passage system and to both of the refrigerant coils. As the liquid passes through the refrigerant coils and drops in pressure, it will expand and absorb heat, being finally collected in the chamber 160. During this expansion, the liquid will freeze the well fluid or the drilling fluid or other liquid in the well bore which surrounds the two upper and lower expansion chambers. This will produce a solid seal obstructing any flow of fluid through the well bore and thus completely isolating the selected zone or region of the strata 12 from the well bore. By now releasing the pressure which was just applied through the 35 tubing 72, 82 in order to actuate the control valve and by forcefully moving the member 58, the shear pin or shear disk 70 will be sheared. This will have the effect of the member 58, and the tube 72, 82 moving upwardly with respect to the members 54, 52 and the sections which lie theretherein so that the inlet portion of the tube 82, indicated by the numeral 170 registers with the passage 112 and permits fluid to be introduced from the tube into the isolated zone for treating the latter, or permits fluid from the zone to be withdrawn through the tubing 40 for testing purposes.

Thereafter, the frozen plugs produced by the refrigerating action may be allowed to thaw or such thawing may be facilitated and hastened by circulating heated drilling fluid through the tubing 72, 82. This will completely 45 remove all sealing means and restore the well bore to its original unimpeded flow condition.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope 50 of the invention as claimed.

What is claimed as new is as follows:

1. An apparatus for use in a well bore having therein a freezable liquid, for temporarily closing said well bore on opposite sides of a selected region to be isolated, said apparatus comprising a refrigerating device sealed from the atmosphere, said device comprising a plurality of connected sections including a pair of refrigerating sections each containing therein in good heat transfer relation therewith a refrigerant expansion chamber, a spacer section interposed between said refrigerating sections and of sufficient length for positioning the latter upon opposite sides of said selected region, a refrigerant storage section having therein a refrigerant storage chamber storing a refrigerating fluid under pressure, at least one of said plurality of sections having therein an exhaust chamber, refrigerant delivery means conducting refrigerant from said refrigerant storage chamber to each of said expansion chambers and refrigerant exhaust means conducting refrigerant from said expansion chambers to said exhaust chambers, a control valve assembly interposed in said refrigerant delivery means and having a control valve controlling flow of refrigerant through said expansion chambers, an actuator means connected to said control valve and effecting positive opening and closing of the latter at selectively controllable times from the surface of the ground.

2. The combination of claim 1 including a pipe string to which said apparatus is connected and supported and whereby said device may be maneuvered and positioned in a well bore, said actuator means being controllable through said pipe string.

3. The combination of claim 1 including passage means in said spacer section establishing communication with said selected region to be isolated, a valve controlling said passage means.

4. The combination of claim 3 including a tube extending through said refrigerating and said spacer sections and being slidably therein, said passage means including registerable ports in said tube and spacer section, releasable retaining means engaging said tube and preventing registry of said registerable ports.

5. The combination of claim 1 wherein said expansion chambers each comprise an expansion coil disposed in one of said refrigerating sections, said expansion coils being connected in parallel relation to said refrigerant delivery means.

6. The combination of claim 5 wherein each expansion coil has an outlet separately communicating with said exhaust chamber.

7. The combination of claim 1 wherein said exhaust chamber is disposed in an exhaust section, said exhaust and refrigerant storage sections being positioned at opposite ends of said refrigerating sections.

8. The combination of claim 1 wherein said control valve assembly includes a valve chamber having an inlet in continuous communication with said refrigerant storage chamber and an outlet communicating with said expansion chambers, said control valve being mounted for movement in said valve chamber and controlling said outlet, said actuator means including an actuator element, means applying fluid pressure to said actuator element and effecting movement of the latter, means connecting said actuator element to said valve.

9. The combination of claim 8 wherein said actuator element consists of a reciprocating piston, said connecting means comprising a cam finger on said piston and a slot in said valve receiving said cam finger, said piston and cam finger being movable transversely of the line of movement of said valve.

10. An apparatus for isolating a selected zone in a well bore having a liquid therein comprising a refrigerating device adapted to be moved in a well bore to said

selected zone, said device including a storage chamber means for a refrigerant under pressure, means defining refrigerant expansion chambers spaced from each other a distance sufficient to enable positioning of said expansion chambers in said well bore on opposite sides of said zone, means for delivering refrigerant from said storage chamber to said expansion chambers, control means operative to control flow of refrigerant from said storage chamber to said delivery means, each expansion chamber having an expansion coil therein, said delivery means comprising a conduit extending into both said expansion chambers and being connected to the expansion coils therein.

11. An apparatus for isolating a selected zone in a well bore having a liquid therein comprising a refrigerating device adapted to be moved in a well bore to said selected zone, said device including a storage chamber means for a refrigerant under pressure, means defining refrigerant expansion chambers spaced from each other a distance sufficient to enable positioning of said expansion chambers in said well bore on opposite sides of said zone, means for delivering refrigerant from said storage chamber to said expansion chambers, control means operative to control flow of refrigerant from said storage chamber to said delivery means, said control means including a control valve operatively interposed between said storage chamber and said delivery means, a fluid pressure operated actuator connected to said control valve, means for applying fluid under actuating pressure to said actuator.

12. An apparatus for temporarily closing a well bore at a selected region comprising a refrigerating device adapted for movement to a selected region in a well bore having a liquid therein, said device including a chamber means for storing a refrigerant under pressure and means defining an expansion chamber for positioning at said selected region, means for delivering refrigerant from said storage to said expansion chamber, control means for controlling refrigerant flow between said chambers, said control means including a control valve operatively interposed between said storage chamber and said delivery means, a fluid pressure operated actuator connected to said control valve, means for applying fluid under actuating pressure to said actuator.

13. An apparatus for isolating a selected zone in a well bore having a liquid therein comprising an elongated refrigerating device adapted for movement in a well bore to and from said selected zone, said device including a unitary body having therein separate upper and lower expansion chambers and a refrigerant storage chamber, said body having a spacer section for separating said expansion chambers by a sufficient distance to locate said expansion chambers on opposite sides of said selected zone, means for delivering refrigerant from said storage chamber to each expansion chamber, means for controlling flow of refrigerant through said delivery means, a conduit in said body, registerable relatively movable means defining ports in said conduit and spacer section openable through said spacer section into said bore at said selected zone for flow of fluid between said conduit and bore.

14. The combination of claim 13 including means for applying fluid under pressure from said conduit to said control means.
